FREDERIC E. BALDWIN, OF NEW YORK, N. Y.

ACETYLENE-LAMP.

1,174,112.

Specification of Letters Patent.

Patented Mar. 7, 1916.

Application filed September 9, 1911. Serial No. 648,503.

To all whom it may concern:

Be it known that I, FREDERIC E. BALDWIN, a citizen of the United States, and a resident of the city of New York, borough 5 of Manhattan, in the county and State of New York, have invented a new and Improved Acetylene-Lamp, of which the following is a full, clear, and exact description.

10 My invention relates to acetylene lamps and comprises a number of distinct improvements all of which, however, are for the general purpose of controlling the flame and protecting the chimney.

15 More particularly stated, my invention comprehends the following purposes, to wit: to provide an elongated tubular connection which shall discharge excess gas at a point remote from the burner so that it will 20 not be ignited by the flame.

Reference is to be had to the accompanying drawing forming a part of this specification and in which like characters of reference indicate corresponding parts, and in 25 which the figure shows a central vertical section through an acetylene lamp made in accordance with my invention.

A generating chamber is shown at 1 and is 30 filled or partially filled in the usual manner with carbid 2. The upper end of the generating chamber is provided with a neck 3 so formed as to present practically a threaded internal surface. A water reservoir is shown at 4, and, like the generating chamber 35 1, is made of sheet metal. The water reservoir is provided with a reduced portion 5 which has generally the conformity of a thread and fits into the threaded neck 3 of the generating chamber. A packing 6 40 which, in this instance, is a rubber ring, is inserted between the water reservoir and the upper portion of the generating chamber for the purpose of rendering these parts gas-tight relatively to each other.

45 The water reservoir 4 contains water 7 and is provided centrally at its bottom with a water tube 8. This water tube is of a length commensurate with other parts, as herein-after described. Extending into the water 50 reservoir 4 is a valve chamber 9 containing a needle valve 10. The valve chamber 9 is, by aid of a tube 11, connected with the generating chamber 1. The lower end of the tube 11 is enlarged and filled with a 55 fibrous mass 12 which serves as a sieve to prevent portions of the carbid from acci-

dentially getting into the tube in case the lamp is turned over.

Connected with the valve chamber 9 is a burner tube 13 carrying a tip 14 encircled by a gas bag 16. This gas bag is generally of an annular form and is provided with necks 17 which fit closely around the burner tube. It serves as an equalizer for the purpose of preventing undue momentary 60 changes in atmospheric pressure from extinguishing the flame.

The top of the water reservoir 4 is shown at 18 and has generally the form of a flat disk. Resting upon this top is a lamp chimney 19 which is merely a cylinder of glass. A number of tubular posts 20 spaced equidistant are disposed around the chimney 19 and arranged generally in the form of a circle. These posts are formed into a circular gallery, and, because of their tubular form are provided with passages 21, some of which may readily be used for pouring water into the water reservoir 4.

A wire 23 extends through one of the tubular posts 20 and is provided at its upper end with a loop 24 serving the purpose of a handle. The wire 23 is of some length and is bent, a portion 23^a extending down through the water tube 8. I designate the 80 wire 23 as a "raking" wire. By pushing it up or down, by aid of the handle 24, it produces a slight agitation of the carbid 2 immediately under the lower end of the water tube 8. This vertical movement of the wire 85 also tends to dislodge any obstruction which may happen to get into the water tube 8; that is, between it and the portion 23^a of the wire.

The diameter of the wire 23, and particularly the diameter of the portion 23^a, is so related to the internal diameter of the water tube 8 that the downward flow of water through the water reservoir 4 and into the carbid chamber 1 is commensurate with the 95 generation of the maximum amount of gas for which the burner is constructed. The water tube 8 is of such length that, when the tube contains the portion 23^a of the wire 23, the diameter of the water tube is 100 practically so restricted as to prohibit the upward passage of gas and the downward passage of water through the water tube at the same moment, but when an excess of gas is generated the excess gas passes upward 105 through the tube 8 and escapes by the tubes 21 or 22 to the atmosphere. In this way 110

the excess gas is discharged at a considerable distance from the burner and the natural currents of air or burned products of combustion tend to keep the excess gas away 5 from the flame. This is of great importance where the carbid is suddenly shaken up, as by dropping the lamp without extinguishing the flame of the burner, since it prevents the ignition of the escaping excess gas.

10 The parts are so constructed that when the generating chamber is filled with carbid and the water reservoir is filled with water and the valve 10 is closed, a few drops of water entering the carbid chamber 1 and 15 generating gas which is now unable to escape, the gas tends to escape by passing upwardly through the water tube 8. This cuts off the supply of water until the water column pressure equals the gas pressure, and 20 when this occurs, no more gas can escape from the carbid chamber nor can any more water enter the carbid chamber. The lamp will remain in this condition indefinitely. If, now, the gas valve 10 is open to its full 25 capacity, the gas pressure suddenly drops and water begins to enter the carbid chamber, this action being very slow, however, owing to the fact that the maximum supply of water is greatly restricted. Without the 30 proper restriction the water would immediately flood the carbid, thus causing a large overgeneration and waste of gas. Upon partially closing the valve 10, the increasing gas pressure cuts off the supply of water 35 until the gas pressure within the lamp falls below the water column pressure, and when this occurs the water will begin to slowly enter the carbid chamber so that the supply of the water will be substantially in proportion 40 to the consumption of the gas.

In lamps of ordinary construction, when built to burn for many hours in succession, the large amount of water consumed causes the water level in the water reservoir to vary 45 by several inches; therefore, as the water in the water reservoir is gradually depleted, the pressure of the water column extending down into the gas generator is gradually lessened, the result being that the flow of 50 water is correspondingly curtailed and, as a consequence, the flame burns lower than desirable. To avoid this difficulty, I make the water tube 8 longer than would otherwise be necessary to obtain a proper maximum 55 amount of water pressure. When the water tube 8 is thus lengthened, its excessive length is rendered, in a great measure, unobjectionable by the action of the wire which it contains; that is to say, the presence of the 60 wire produces a retarding effect upon the downward flow of water through the water tube, the net result being that the downward flow of water is comparatively steady, but that variations in its pressure, due to variations 65 in the depth of water contained at

different moments in the water reservoir, are rendered less pronounced as affecting the actual quantitative flow of water into the gas generator. The tubes 20 are of such length that though open and connected with 70 the water container, they prevent the water in the container from splashing up and coming in contact with the chimney under any ordinary conditions of use.

To illustrate, a lamp having a water reservoir three inches deep and a water tube six inches long would afford a water pressure equal to that of a water column nine inches in height. If, now, a wire be inserted (see wire 23^a), the effective water pressure 75 is reduced, and if the parts be at all properly proportioned, the pressure can readily be limited to that of a water column two and three-quarter inches in height. This being true, it follows that each inch of the virtual 80 length of the water column produces, in practice, a pressure representing that of a water column one-third of an inch in height. Since, therefore, the three inches of water in the lamp constitute, for purposes of pressure 85 efficiency, a column only one inch in height, if the water tube 8 be so proportioned as to work at the mean water pressure level of the reservoir, there is a variation, during the entire time while the lamp is burning, of a pressure representing that of a water column 90 only one-half inch in height. This slight variation, in lamps of this type, is in practice negligible.

As may be seen from the foregoing remarks, the lamp is regulated partly by restricting the downward flow of water from the reservoir into the carbid chamber and partly by the direct pressure of the gas acting upon the column of water thus restricted. It follows as a necessary consequence 100 that the flow of water is practically regulated by adjustment of the flow of gas to the burner.

I find that a steady burning of the lamp 105 with a flame of substantially uniform brilliancy is easily accomplished in the manner just described; that is to say, I provide practically a water column of considerable height 110 from the upper level in the water reservoir to the bottom of the generating chamber containing the carbid, and then restrict the downward flow of water from the water reservoir into the gas generating chamber. The retarding influence seems to be the friction 115 of the water as it insinuates itself between the portion 23^a of the raking wire 23 and the inner surface of the water tube 8. No doubt, along with the friction, there is also retardation due to capillarity. The cause of retardation appears to be partly 120 friction and partly capillarity, and seems independent of the variations in hydraulic pressure due to depth of the water column. At any rate, the retardation has a marked 125 130

tendency to steady the flow of water independently of variations in the total depth of the water column.

A shield 25, made in this instance of sheet metal, and having a generally frusto-conical form, is provided with air holes 26 and with an annular flange 27. This flange rests upon the upper end of the lamp chimney 19. A cylinder 28 encircles the shield 25 and is provided internally with an annular flange 29. The cylinder 28 is further provided with air holes 30. Two conical members 31, 32 made of gauze, and each having a substantially frusto-conical form, are fitted together concentrically and are provided with annular flanges 33. These conical members of gauze together constitute a so-called "safety" gauze for the lamp. The flanges 33 are clamped between the flange 29 and the flange 27. A hood 34 is mounted upon lugs 35 carried by the cylinder 28 and constitutes, as usual, the roof of the lamp. The hood 34 carries an eye 36, and engaging the latter is a hook 37 whereby the lamp may be suspended. The shield 25 is for the purpose of preventing the flame of the lamp from reaching the safety gauze and burning through the same, a result which might otherwise take place in the event that the flame is unduly elongated, as, for instance, whenever there is an excess of gas generation. No matter how great may be the volume of the flame from the burner, the flame cannot reach the gauze, and, indeed, cannot extend very high for the reason that it reaches a volume of "dead" air or incom- bustible gas housed within the upper portion of the shield 25. I do not limit myself to this particular form of shield, nor to the use of metal in its construction. Obviously, the shield may be made of any suitable fire- proof material, such, for instance, as asbestos. If the shield 25 be made of consider- able height, as shown, and provided with air holes 26, the flame, if unduly elongated, will have a tendency to reach up into the shield,

but owing to the fact that oxygen is not sup- plied in through the shield at any point above the location of the air holes 26, the flame does not in fact reach to the top of the 50 shield 25, and, consequently, does not unduly heat this shield. The safety gauze is thus protected from injury, due to excessive heat of the flame. I find that this arrange- ment works well in practice; so much so that 55 the flow of gas may be suddenly turned on and may have considerable force and yet the safety gauze is not unduly heated, whereas under the same conditions, but without the shield 25, the gauze would be 60 destroyed in a few seconds.

Certain features described and not claimed herein, are claimed in my pending applica- 65 tion Serial No. 689,766, filed April 10, 1912.

I do not limit myself to the precise mech- 65 anism shown, as variations may be made therein without departing from the spirit of my invention, the scope of which is commen- surate with my claim.

Having thus described my invention, 70 what I claim as new and desire to secure by Letters Patent is:—

An acetylene gas lamp comprising a carbid container, a burner, a chimney surround- 75 ing said burner, a water container located below said burner, metal posts extending upwardly above the water tank and protect- ing said chimney, at least one of said metal posts being tubular and communicating with the water container and adapted to 80 carry off the gas generated in excess of the requirements of the lamp, said tubular post discharging said excess gas at a point re- mote from the burner.

In testimony whereof I have signed my 85 name to this specification in the presence of two subscribing witnesses.

FREDERIC E. BALDWIN.
